UNITED STATES PATENT OFFICE.

AXEL J. ROSELL, OF BROOKLYN, NEW YORK.

COUNTERWEIGHTED SIDEWALK ELEVATOR.

Application filed June 17, 1926. Serial No. 116,666.

The present invention is concerned with the provision of a counterweighted side walk elevator of the type commonly employed for hoisting ashes or transferring merchandise 5 from the side walk to the basement.

An object of the invention is to provide a counterweighted elevator of this character so constructed that there is no danger of the elevator moving in any direction unless the 10 operator is turning the handle. Means are provided for automatically locking the elevator against accidental movement, even though the counterweight be considerably heavier than the load on the platform, and 15 even though the load on the platform predominates over the counterweight. In other words, torque on the operating shaft produced by the counterweight or the load on the platform, will simply serve to lock the 20 device against operation, and movement of the elevator up and down in its shaftway can be accomplished only when the operating shaft is manually turned with sufficient force to overcome the weight difference between the load on the platform and the 25 counterweight, regardless of which weight predominates.

A further object of the invention is to provide a counterweighted side walk elevator in which all of the operating mechanism is mounted on, or carried by the platform. This construction renders the operating mechanism always readily accessible for purposes of cleaning or repair, and 30 eliminates the conventional practice of mounting driving wheels or kindred apparatus in the bottom of the shaftway.

Other objects of the invention are to provide a counterweighted side walk elevator, of simple, practical construction, which will be rugged, durable and efficient in use, absolutely fool-proof in operation, and which will lend itself to manufacture and installation with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a view in vertical section through an elevator shaftway showing my improved

elevator in position therein. This view is taken on the line 1—1 of Fig. 2.

Fig. 2 is another vertical sectional view at right angles to Fig. 1, taken on the line 2—2 of Fig. 1.

In the drawings I have used the reference character 10 to designate a side walk, and 60 11 an elevator shaftway sunk downwardly from the side walk and communicating near its lower end with an opening 12, which in 65 accordance with conventional practice may represent an entrance from the basement 13 of a building. The shaftway extends to a sufficient distance between the basement floor to provide ample clearance for the 70 mechanism hung under the platform 14 of the elevator.

Any suitable number of vertical guide rails 15 are mounted at the sides of the shaftway 11, and serve to guide the vertical 75 sliding movement of the platform 14. At the back of the shaftway there is a vertical partition member 16 spaced a slight distance from the rear wall 17 of the shaftway. Partition 16 cooperates with a second short 80 partition 18 to provide a compartment at the rear of the shaftway, in which the counterweight 19 and its associated mechanism are accommodated.

Depending from the platform 14 are a 85 pair of relatively wide hanger plates 20. Sectional bearings 21 carried by the lower edges of the hanger plates, conveniently serve to journal a transverse drum shaft 22 mounting drums 23 and 24 on its ends. A 90 relatively large sprocket wheel 25 keyed to the drum shaft 22 is connected by a sprocket chain 26 to a sprocket wheel 27 mounted on a shaft 28 borne in a skeleton frame 29 supported on and rising from the platform 14. 95

Keyed to the same shaft as the sprocket wheel 27 is a relatively large gear 30 meshing with a pinion 31 on the driving shaft 32 of the elevator. This driving shaft carries a suitable operating crank handle 100 33, and on the driving shaft there is mounted a clutch of conventional construction designated generally by the reference character 34. The purpose of the clutch will be more fully hereinafter set forth.

Each of the drums 23 and 24 has wound thereon a cable 35, the upper ends of these cables being anchored to suitable anchorages at 36 near the upper end of the shaftway. Thus, rotating the drums in a counter-clock- 110

wise direction will tend to wind the cables 35, and move the elevator from the position illustrated, toward the top of the shaftway.

5 Wound on the drum 23 in the opposite direction to the winding of the cable 35 is a counterweight cable 37 passed over a suitable pulley 38 mounted on a bracket 39 at the upper end of the shaftway, and then passed under the pulley 40 from which the counterweight 19 is suspended by a hanger 41. It will be seen that the counterweight 19 tends to rotate the drums in a counter-clockwise direction and moves the elevator toward the top of the shaftway.

10 In order to keep slack out of the cables 35 and 37, a third cable 45 is wound on the drum 23, run under a pulley 46 in the bottom of the shaftway and connected through 15 a coiled tensioning spring 47 to an anchored turnbuckle 48.

15 The details of construction of the clutch 34 form no part of the present invention, the clutch being of a standard type and 20 widely used in various forms of machinery. The clutch may be of the general character disclosed in the Powers Patent No. 1,558,042 of October 20, 1925. The function of the clutch is to lock the shaft 32 against rotation when torque is imparted to this shaft by the weight of the platform or the counterweight. In other words, a material difference in weight between the platform and counterweight are inoperative to effect 25 movement of the elevator, since the clutch automatically locks the gear train against movement. When however, the handle 33 is grasped and turned so that the load is transmitted to the clutch, the gear train will be active to operate the drums 23 and 24, and 30 through the cables above described, move the platform either up or down on its guides 15.

35 It is to be noted that all of the operating mechanism including the drum shaft and drums are carried by the platform 14, and the common inconvenience of mounting machinery in the bottom of the shaftway is eliminated. Consequently, the operator

is always with the load on the platform. 50 The need for the services of two men, one to operate the machinery in the basement, and the other to handle the loading and unloading of the elevator is obviated.

55 While the operation of the device will be readily understood from the foregoing description, it may be briefly noted that when the shaft 32 is rotated by the crank handle 33 in a clockwise direction, the drum shaft will be rotated in a counter-clockwise 60 direction, winding the cables 35 and permitting the cables 37 and 45 to unwind as the platform moves toward the top of the shaftway. When the driving shaft 32 is turned in a counter-clockwise direction, the drum shaft will be rotated in a clockwise direction, winding the counterweight 37 and the tensioning cable 45 and permitting the lifting cables 35 to unwind as the car moves toward the lower end of the shaft. 70

75 Various changes and alterations might be made in the general form and arrangement of parts described without departing from the invention. Hence I do not wish to limit myself to the details set forth, but shall 80 consider myself at liberty to make such changes and alterations as fairly fall within the spirit and scope of the appended claims.

I claim:

85 1. In a side walk elevator, the combination with a shaftway, and platform guided for vertical sliding movement in the shaftway, of a drum shaft hung from and journaled below the platform, drums on the ends of the shaft, lifting cables wound on the drums and anchored near the top of the shaftway, a counterweight, a counterweight cable wound on one of the drums, a frame mounted on the platform, a train 90 of driving gears supported by the frame and connected to the drum shaft, and a tensioning cable anchored in the bottom of the shaft and wound on one of the drums.

95 2. A device as set forth in claim 1, and wherein an automatic clutch on the drive shaft prevents the weight of the platform or counterweight from turning the shaft.

AXEL J. ROSELL.
